UNITED STATES PATENT OFFICE.

CARL P. ASTROM, OF EAST ORANGE, NEW JERSEY, ASSIGNOR TO M. H. TREADWELL COMPANY, OF NEW YORK, A CORPORATION OF NEW YORK.

CAR.

1,080,620.

Specification of Letters Patent.

Patented Dec. 9, 1913.

Application filed April 3, 1912. Serial No. 688,263.

To all whom it may concern:

Be it known that I, CARL P. ASTROM, a citizen of the United States of America, residing at East Orange, in the county of 5 Essex and State of New Jersey, have invented certain new and useful Improvements in Cars, of which the following is a full, clear, and exact specification.

This invention relates to vehicles, and 0 particularly to cars adapted to run on a set of rails.

More particularly, this invention relates to an improved construction of the running gear and means for mounting the body of 5 the car on the same.

I contemplate applying my invention to cars for hauling such material as coal, ore, and the like, usually stored in piles, and desired to be transferred by car loads to another location. In view of such use, I have 20 provided my car with wheels which are adapted to run on a set of rails and also on any approximately smooth surface; however, this particular feature may be varied 25 according to the purposes to which my invention may be put.

An object of my invention is to devise a running gear whereby the car may be run around rail curves of much less radius of 30 curvature than is possible with arrangements heretofore proposed. To this end, I provide movable axles which are pivoted to the body or frame of the car, such axles being joined in pairs by interconnecting 35 links, preferably somewhat yieldable, said links extending from diagonally disposed points of the two axles.

Another object of this invention is to provide a car which can be run around a curve 40 defined by two or more rails with minimum effort, and at the same time to be stable when moving around such curve at a comparatively high speed.

Other objects and features of my invention will be more fully understood from the 45 following description and the accompanying drawings, in which—

Figure 1 is a side elevation of a car embodying my invention, a portion thereof 50 being shown in dotted lines to indicate the dumping position of the car; Fig. 2 is a front elevation of the car shown in Fig. 1; and Fig. 3 is a plan, partly in section, of the running gear of the car shown in the 55 preceding figures, illustrating the positions

of the parts when the car is drawn around a rail curve.

Referring to the drawings the body 1 is shown as pivotally mounted on the frame 2. In normal position, the body is retained in 60 horizontal position by the lever 3, shown as pivoted on the body 1 and adapted to engage the lug 4 on the frame 2, the catch 5 serving to lock the lever 3 in retaining position. In the car illustrated in the drawings, 65 two axles 6, 7 are employed, although any plurality of axles may be used. The axles 6, 7 are held by the bolsters 8 pivoted to the frame 2 by king pins 9. The link 10 extends from the eye-lug 11 positioned at or 70 near one end of the axle 6 to the eye-lug 12 positioned at or near the opposite end of the axle 7. The link 13 extends from the eye-lug 14 positioned at or near the other end of the axle 6 to the eye-lug 15 disposed 75 at or near the opposite end of the axle 7. The link 13 is provided with a bent portion 16 to avoid interference with the link 10, and also serves to give sufficient resiliency to the link 13 and thereby to the axles when 80 the car is drawn around curves, and also when striking obstacles, and under other conditions, as will be understood. The bent portion 17 of the link 10 provides the desired resiliency for the link 10. The loose 85 wheels 18 are positioned at the ends of the axle portion 19, and held thereon by nuts 20. Each wheel 18 comprises an inner tread 21 of relatively smaller diameter, and an outer flange and tread 22 of larger diameter, 90 the latter serving as a flange when the inner tread 19 rides upon the surface of the rails.

Fig. 3 illustrates the positions of the axles and wheels with respect to the rails R when 95 running around the curves, and it will be observed that the car will be run with minimum effort around a rail curve of appreciably low radius of curvature. In the particular form illustrated in Fig. 3, the pivoted axles 16 assume positions substantially in alinement with the radius of the curve of the rails. Thus, when the car runs around the rail curve, the wheel portions 21 serve as the tread, and the outer wheel portions 100 105 22 serve as flanges, the face of which is preferably at right angles to the surface of the tread.

It will be seen that the operation of this invention in trucks when running upon rails 110

depends upon the flanges being at the outside of the wheels, since inside flanges would not operate. In going around a curve, the outside flange of the inner wheel will strike the 5 outer edge of the rail first, which engagement will tend to hold this end of the axle relatively still, allowing the outer end of the axle to swing around the outer arm of the curve. This pivotal movement of the forward 10 axle is transmitted by the crossed links to the rear axle, which tends to swing oppositely to the forward axle, to such extent as is permitted by the normal clearance between the flange and the rail. The car being in motion during this time it will, of course, 15 be seen that these two trucks by the co-operating links tend to automatically position themselves on radii of the curve, and consequently to go around curves of very short 20 radius with a minimum of effort. The handle 23 operates in the same manner as the flange when the truck is not running on rails, since the act of turning the handle to one side or the other to turn the axle to which it 25 is connected, will automatically turn the other truck, so that the axles will move oppositely to each other and enable very short curves to be turned.

When the car is drawn off the rails, the 30 larger wheel portions serve as the tread. It will be clear that the inner wheel portion need not be integral or fixed to the outer wheel portion, and both wheel portions may be loose on the axles. The handle 23 is suitably connected to an axle of the car, as by the spaced lugs 24, and thus by turning the handle to either side, the pivoted axles are 35 oppositely rotated. The inclines 25 are provided at the ends of the rails for readily drawing the car on and off the same.

It will be understood that many changes 40 and modifications may be made in the specific arrangement illustrated without departing from my invention.

What I claim is new and desire to secure 45 by Letters Patent is:

1. A car comprising in combination a

frame, a pair of axles pivotally mounted thereon, wheels positioned at the ends of said axles, and links connecting said axles at diagonally oppositely disposed points, each of said wheels comprising an inner tread portion and having but a single flange, said single flange being disposed exteriorly of said tread portion and of relatively greater 55 diameter.

2. In a car, the combination of a frame, a plurality of axles pivotally connected thereto at central points thereof, links for connecting said axles at diagonally oppositely disposed points, and wheels mounted at the extremities of said axles, said wheels having an inner tread portion and but a single flange portion, said flange portion being adapted to engage the exterior vertical face 65 of a rail.

3. A car comprising in combination a body, wheel axles pivotally connected thereto, crossed links connecting said axles at oppositely disposed points, and wheels mounted at the extremities of said axles, certain of said wheels being loosely mounted on their respective axles each of said wheels comprising an inner tread portion and having but a single flange, said flange being of larger diameter and adapted to engage the rail on the 75 outside thereof.

4. A car comprising in combination a body, wheel axles pivotally connected thereto, diagonally disposed links connecting said 80 axles at points adjacent the ends thereof, one of said links being provided with a bent loop portion to provide limited resilience against thrusts, and wheels mounted at the ends of said axles, each of said wheels comprising 85 a tread portion and having but a single rail engaging flange, said flange being positioned on the outer side of said tread portion.

In testimony whereof I affix my signature, in presence of two witnesses.

CARL P. ASTROM.
